UNITED STATES PATENT OFFICE.

WARREN E. KEPLINGER, OF CINCINNATI, OHIO.

PAPER-SHELL CARTRIDGE.

1,184,753.

Specification of Letters Patent. Patented May 30, 1916.

Application filed October 26, 1914. Serial No. 868,575.

To all whom it may concern:

Be it known that I, WARREN E. KEPLINGER, a citizen of the United States, residing at Cincinnati, in the county of Hamilton and 5 State of Ohio, have invented a new and useful Improvement in Paper-Shell Cartridges, of which the following is a specification.

My invention relates to cartridges and more particularly to paper shell cartridges, 10 such as are used in shotguns and the like.

The object of my improvement is the provision of a cartridge of the kind mentioned which is provided with means for reinforcing the paper tube portion of the cartridge, and especially the point of the latter at and near the top edge of the metallic cap portion.

Other objects will appear hereinafter.

The invention consists in substantially 20 combination and arrangement of parts hereinafter described and claimed, and will be best understood by reference to the accompanying drawing, forming a part of this specification, and in which—

25 Figure 1 is a longitudinal section of a cartridge embodying my invention; Fig. 2 is a section taken on line 2—2 of Fig. 1; Fig. 3 is a plan view of a sheet of paper provided with reinforcement used in the manufacture 30 of my improved shell, Fig. 3 being on a smaller scale than Figs. 1 and 2; Fig. 4 is a section taken on the line 4—4 of Fig. 3, but having its thickness exaggerated; Fig. 5 is a 35 perspective view of a cartridge, having portions of it torn up to show its construction; Fig. 6 is an enlarged fragmental section of a sheet of material from which a cartridge embodying my invention is produced, and in which the reinforcing member is 40 bedded in the sheet; and Fig. 7 is a similar view showing a different form of reinforcing member.

In the use of paper shell cartridges, the 45 paper tube portion is frequently broken at the point where it meets the top edge of the metallic cup portion by the explosion of the charge in the cartridge. This breaking of the paper shell, which is ordinarily called "cut-off", causes considerable inconvenience 50 in the use of this class of cartridges, and of course prevents their being re-used and so makes them unduly expensive. Various methods have been adopted to prevent "cut-offs" in paper shell cartridges, which have 55 been more or less successful, but not entirely so. To overcome this fault, I reinforce the

paper shell at the point where the "cut-off" is likely to occur.

I find that a material such as a fabric of cotton, linen, silk, wire mesh or the like makes a desirable reinforcing member. A thin sheet of metal, fiber, or the like, either imperforate or foraminate, may also be employed with equally good results. Wire or threads (not shown) may also be embedded in the paper of the tubes to form the reinforcement therefor. I prefer to embed the reinforcing element in the paper of the tube, but when so desired it may be placed on the inner side or outer side of the latter, without departing from my invention. The reinforcement is not shown as disposed on the inner or outer side of the cartridge in the drawing, but it will be readily understood how this may be applied from perusing the method of embedding in the paper of the tube.

In the improved tube of my cartridge, preferably use a sheet of paper 10, or other suitable substance, Fig. 3, and secure a reinforcing element 11 of fabric, or the like, to the sheet. The reinforcing element is preferably of a width and disposed on the sheet in a manner so that when the sheet and reinforcing element are rolled and formed into a tube in the usual manner, the reinforcing element will cover at least one of the convolutions of the sheet and be embedded in the tube between the convolutions of such tube. For a convenient and economical manufacture of the cartridges, I find that the reinforcing element may be disposed longitudinally of the sheet, and, when rolled and cut on lines substantially indicated by the dotted lines 12 in Fig. 3, will form tubes of proper lengths for the cartridges. However, when so desired, the reinforcing element 11 may be made co-extensive with the sheet 10, or it may be made in such sizes that when applied to the sheet it will only extend over sufficient part of the tube to protect the portion thereof where the "cut-offs" occur.

The tubes after having been prepared as described above, are secured between the metallic cup member 13 and the base wad 14 of the cartridge, in the usual manner. The metallic cup 13 and base wad 14 may be of conventional or any desired construction. When so constructed, the reinforcing element 11 provides a means whereby the paper tube or shell of the cartridge is strengthened in a manner to prevent the explosions of the

charges in the cartridges from breaking or cutting off the paper tube at a point near the top edge of the metallic cup 13.

The reinforcing element 11 may be secured to the sheet 10 in any desired manner. In Fig. 3, I have indicated a construction in which the reinforcing element is secured to the sheet 10 by means of an adhesive. In Fig. 6, I have shown the reinforcing element 10 as having been pressed into the sheet of paper, such as by running the reinforcing material through the rolls of the paper-making machine during the manufacture of the paper. In Fig. 7, I have indicated the 15 reinforcing material formed of a solid sheet and applied to the sheet 10.

While I have illustrated and described the preferred form of construction of my invention, I do not desire to be limited to the 20 precise details described and shown, but desire to avail myself of such variations and changes as come within the scope of the appended claims.

I claim:

1. A cartridge comprising a paper tube 25 made up of a sheet disposed in a plurality of convolutions secured together; a cloth reinforcing member positioned between two convolutions of the paper sheet; and a cup secured to and inclosing one end of the 30 paper tube.

2. A cartridge comprising a tube made up of a sheet of paper disposed in a plurality of convolutions and a narrow sheet of cloth extending around and pressed into 35 one of the intermediate convolutions of the paper sheet; and a cup secured to and inclosing one end of the tube.

In testimony whereof I have signed my name to this specification, in the presence of 40 two subscribing witnesses, on this 22nd day of October A. D. 1914.

WARREN E. KEPLINGER.
